(57) **CLAIM**

The ornamental design for an automobile tire, as shown and described.

DESCRIPTION

FIG. 1 is a front perspective view of an automobile tire showing our new design;

FIG. 2 is a rear perspective view thereof;

FIG. 3 is a front view thereof; top plan and bottom plan views are the same as the front view.

FIG. 4 is a rear view thereof;

FIG. 5 is a left side view thereof;

FIG. 6 is a right side view thereof; and,

FIG. 7 is an enlarged fragmental front view taken along lines 7-7 in FIG. 3.

The broken lines in the drawings are for the purpose of illustrating unclaimed portions of the tire and form no part of the claimed design.
